(57) **CLAIM**

The ornamental design for a square drill bit, as shown and described.

DESCRIPTION

FIG. 1 is a perspective view of a square drill bit according to the present invention;

FIG. 2 is a top plan view of the square drill bit of FIG. 1;
FIG. 3 is a front view of the square drill bit of FIG. 1;
FIG. 4 is a back view of the square drill bit of FIG. 1;
FIG. 5 is a left side view of the square drill bit of FIG. 1;
FIG. 6 is a right side view of the square drill bit of FIG. 1; and,

FIG. 7 is a perspective view of the driver drill bit of FIG. 1 in co-operation with a crown bit, wherein the broken lines illustrate components that form no part of the design.
The broken lines in the figures are for illustrative purposes only and form no part of the claimed design.

UNITED STATES PATENT AND TRADEMARK OFFICE
CERTIFICATE OF CORRECTION

PATENT NO. : Des. 496,948 S
DATED : October 5, 2004
INVENTOR(S) : Luc Charland et al.

Page 1 of 1

It is certified that error appears in the above-identified patent and that said Letters Patent is hereby corrected as shown below:

Title page,

DESCRIPTION,

Fig. 1, the term "present invention" should read -- present design --

Fig. 7, the term "driver drill bit" should read -- square drill bit --

Signed and Sealed this

Fifth Day of April, 2005

A handwritten signature in black ink, appearing to read "Jon W. Dudas". The signature is written in a cursive style with a large, stylized "J" and "W".
